(57) CLAIM

The ornamental design for a buffing pad, as shown and described.

DESCRIPTION

FIG. 1 is a front perspective view of an example of a buffing pad according to the invention.

FIG. 2 is a bottom view of the buffing pad shown in FIG. 1.

FIG. 3 is a top view of the buffing pad shown in FIG. 1.

FIG. 4 is a bottom view of the buffing pad shown in FIG. 1.

FIG. 5 is a front side view of the buffing pad shown in FIG. 1.

FIG. 6 is a back side view of the buffing pad shown in FIG. 1.

FIG. 7 is a left side view of the buffing pad shown in FIG. 1; and,

FIG. 8 is a right side view of the buffing pad shown in FIG. 1.

The broken line showing of the bottom portion of the buffing pad in FIGS. 2, 4, and 5-8 is for illustrative purposes only and forms no part of the claimed design.
